Specification for Design.

Patented Feb. 1, 1921.

Application filed April 14, 1920. Serial No. 373,974. Term of patent 3½ years.

To all whom it may concern:

Be it known that I, GEORGE RUDROFF, a citizen of the United States, and a resident of Richmond Hill, in the county of Queens and State of New York, have invented a certain new, original, and ornamental Design for Match-Box Holders, of which the following is a specification, reference being had to the accompanying drawing, forming a part thereof.

The figure is a perspective view of my match box holder, showing my design.

I claim:

The ornamental design for a match box holder as shown.

GEORGE RUDROFF.
